UNITED STATES PATENT OFFICE.

ELIHU THOMSON, OF NEW BRITAIN, CONNECTICUT, ASSIGNOR TO THE THOMSON-HOUSTON ELECTRIC COMPANY, OF CONNECTICUT.

ELECTRIC-ARC LAMP.

SPECIFICATION forming part of Letters Patent No. 447,383, dated March 3, 1891.

Application filed February 16, 1884. Serial No. 121,023. (No model.)

To all whom it may concern:

Be it known that I, ELIHU THOMSON, a citizen of the United States, and a resident of New Britain, in the county of Hartford and 5 State of Connecticut, have invented certain new and useful Improvements in Electric-Arc Lamps, of which the following is a specification.

My invention relates to the general construction of electric-arc lamps; and it consists in certain combinations and details of construction, which will be hereinafter described, and pointed out in the claims, and which are designed, among other things, to render feasible 10 the employment of carbons of small diameter, as also to reduce the length of the lamp and render the lamp more convenient of use.

In the operation of electric lamps it is found that with the ordinary constructions there 15 is considerable difficulty in keeping the carbons, especially if of small diameter, in strict alignment during burning. Lamps constructed for the employment of carbons as small as three-sixteenths to one-fourth of an 20 inch in diameter have often failed from this cause. In my lamp this difficulty is avoided by a novel combination with the carbon-carrier of a central bushing and guides, the latter connected with the carrier near the carbon-holder and arranged to bear on side rods 25 or guides, preferably below the level of said holder. In my lamp, moreover, the construction is such that the globe may be lowered to 30 permit renewal of the carbons, while at the same time the arrangement is such that no 35 addition to the length of the lamp is required to secure this result.

Figure 1 is an elevation of a lamp constructed according to my invention. Fig. 2 40 is a detail side view of the clamp or clutch employed with the carbon or carbon-carrier. Fig. 3 is a longitudinal cross-section of one side of the guide and the guide-rod upon which it bears. Fig. 4 is a vertical section of 45 the lower-carbon clamp or holder. Fig. 5 is a detail perspective view of the pivoted ring-clamp and rod by which the globe is suspended.

Any magnet system may be employed in 50 the lamp to effect the separation of the car-

bons and the release or feed of the same as they waste away.

D and S indicate coarse and fine wire magnets of any suitable or ordinary shape, one to be placed in main or principal and the other in a derived circuit around the carbons, as usual in the art, while D² indicates an armature controlled by said magnets and serving to impart movement to the clamp, clutch, or other feed-controlling device. These parts 55 are merely typical of such devices in lamps, and need not be described further.

R is the upper carbon rod or carrier, which is guided in a hole in the bottom of the case H. It is furnished with a cross-head or support Y, which sustains two pieces K, forked or perforated, so as to be guided upon the side bars or parallel guide-rod G G, depending from the lamp. The position of the points of contact of the pieces K K with respect to the carbon holder or clamp E is preferably, as shown, some distance below the latter. This device, acting in conjunction with the hole or guide in H, serves as an excellent steadyng and guiding arrangement 65 for preventing lateral displacement of the holder E and consequent sliding by one another of the small carbons used. The guide-pieces K K are insulated from the cross-head 70 or support Y in case the guide-bars G G are 75 also in electrical connection with and serve as the means of sustaining the lower-carbon holder F, as in the present and preferred construction of electric lamps. The guide-bars G G are hung from an insulated plate P under 80 the lamp-case itself.

To avoid unnecessary length of the rod R, the actuating-clutch C is placed immediately above the hole or bushing H. This clutch may be any construction adapted to be operated in the position shown. A form suitable for the purpose consists of a body c, Fig. 2, with a hinged cam or jaw J, having an elongated arm extending in a vertical direction, as shown, and provided with a spring s, 95 acting to close said jaw J upon the rod R. The body c is supported by a link hung from a horizontal arm D⁴, extending from the fulcrum-point of the armature-lever D². The jaw J is released on the lowering of the clutch 100

by a bent or elbow lever *b*, which, being pivoted on the arm *D*⁴, is lowered with the clutch, and by striking a fixed stop *a* is caused to force the jaw *J* to open and drop or release the rod *R*. The magnets *D* and *S*, Fig. 1, act in the ordinary way upon the clutch.

In the drawings, Fig. 3, the bearing of the piece *K* on the guide-rod is more clearly shown with its interposed insulating material *I*, of asbestos, paper, or other suitable material.

The globe is supported in a ring *O* below the lower-carbon holder *F*, said ring being preferably kept from coming into electrical connection with the holder or its support by means of a piece or pieces of insulating material *I*², secured to the ring *O* or to the holder *F* or its support. The ring or support *O* is itself supported by side rods *M M*, which extend upward around the outside of the globe, and may be moved up and down in suitable guides.

Guides *D*⁵ *D*⁶ are supported by or from the lamp-case, and preferably insulated therefrom. *N N* indicate tilting clamps or clutches which are pivoted at one side on stationary supports and surround the rods *M M*, so as to normally grasp said rods and hold them and the globe-holder up while the lamp is in use. When the globe is to be lowered for renewal of carbons or the like, the tilting catches *N N* are simply lifted to a horizontal position, when the globe and side rods may be let down until the stops *T T* upon the upper ends of the rods *M* come into engagement with the catches *N N*.

Fig. 5 shows the catch *N* clamping its bar or rod *M*.

The lower-carbon holder *F* is mounted, as shown in Fig. 4, so as to permit a slight ball-and-socket or universal swinging movement to be given to it, so as to bring the end of the lower carbon opposite the end of the upper carbon. *G*⁴ is the lower cross bar or plate carried by the rods *G G* and supporting the lower-carbon holders *F*.

The holder *F* is itself of any suitable or proper construction for clamping or grasping the lower carbon. The plate *G*⁴ is centrally perforated for the admission of the body of

the holder *F*, extended downward for the reception of a nut *V* screwing thereon. The surfaces of *G*⁴, of *F*, and of *V* fit one another upon curved lines, the curves of which are concentric, centering preferably a little above the holder *F*. The nut serves to clamp the parts in any desired position. When it is loosened, the lower carbon may be pointed in any direction so as to effect a compensation for slight crookedness of carbons.

What I claim as my invention is—

1. The combination, substantially as described, of the upper-carbon rod or carrier guided in a bushing at the bottom of the lamp-frame, a cross-bar *Y*, carrying guide-pieces supported by said bar below the carbon-clamp and guided upon the side rods that support the lower carbon, a lifting and feed clamp supported immediately above the bushing at the lower part of the lamp-frame, a lever *D*⁴, sustained by said clamp and carrying the armatures for the lamp-magnets, the vertical arm or extension from the feed-clamp, a releasing elbow-lever carried by the lever *D*⁴ and arranged to engage said vertical extension, and a stop for the horizontal arm of said lever, as and for the purpose described.

2. The combination, substantially as described, in an electric-arc lamp, of rods *G G*, carrying the lower carbon, the globe surrounding said rods, exterior rods *M*, supporting the globe-holder, and the tilting clamps or clutches *N*, supported from the side of the lamp-casing, as and for the purpose described.

3. The combination, in an electric lamp, of the globe-holder, the vertically-sliding rods *M*, supporting the same, and having stops *T* at their upper ends, guides *D*⁵ *D*⁶, secured to the lamp-casing, and clamps or clutches *N N*, supported from the lamp frame or case above said guides, as and for the purpose described.

Signed at Boston, in the county of Suffolk and State of Massachusetts, this 3d day of November, A. D. 1883.

ELIHU THOMSON.
